KARL R. SCHUSTER, OF NEW YORK, N. Y.

CONCRETE BUILDING CONSTRUCTION.

1,134,164.

Specification of Letters Patent. Patented Apr. 6, 1915.

Application filed April 12, 1910. Serial No. 554,982.

To all whom it may concern:

Be it known that I, KARL R. SCHUSTER, of the borough of Manhattan, city and State of New York, have invented certain new and useful Improvements in Concrete Building Constructions, of which the following is a full, clear, and exact specification, such as will enable others skilled in the art to which it appertains to make and use the same.

16 This invention is a floor construction for fire proof buildings, the latter embodying usually a framework composed of steel and concrete or steel and stone or brick, such as are now used extensively for manufacturing and business purposes; and said invention pertains, more particularly, to a floor construction wherein hollow blocks or tiles are combined with concrete in such a manner as to result in a floor or flat slab between 20 girders, which floor is so reinforced as to render it self-sustaining without resorting to the use of intermediate beams. In this art the developments in recent years have been such as to create a demand for a structure 25 combining the minimum of weight with a maximum of strength to resist the full quota of bending stresses under an abnormal load, but chiefly the requirements are for economy in the use of materials, and the capacity of 30 installing the components of the floor by unskilled labor.

Accordingly, the objects of my invention are to meet these requirements by a form of construction which embodies the necessary 35 strength to meet the various stresses, requires the least possible dead weight in the materials, which attains marked economy in the use of materials, and which can be installed rapidly and easily by unskilled labor.

40 It is recognized that a perfect bond is obtainable between hollow clay tile blocks and plastic concrete or mortar provided the tile blocks be set while dry and cement in a plastic or semi-plastic condition be poured into the spaces between the tile blocks and properly tamped, as a result of which the concrete and tile blocks unite or bond so intimately as to result in a monolith between the girders and piers or columns. It may be stated that 45 tile blocks are employed chiefly as the filler material to secure economy, to expedite the installation, and to reduce the aggregate weight of the flat slab or floor construction; but serious problems have always heretofore 50 presented themselves to engineers and con-

tractors in so combining the tile blocks and the concrete material that the resulting floor construction will, or can be made to, utilize the full compressive strength of the material present in the hollow tile blocks, to bind the 55 hollow blocks and the material of the concrete beams in a manner to minimize the entry of the plastic or semi-plastic concrete during the operation of installing the components of the floor, and to so bond the hollow tile blocks and the concrete as to attain 60 homogeneity of structure, resulting in a monolith possessing the requisite strength and load carrying capacity with a minimum of weight for slabs of definite area between 65 the girders and columns or piers.

I am aware that concrete and hollow tile floors have been crosswise reinforced by spacing blocks of a certain form in such 70 manner that crossing or intersecting metal rods may be positioned in two directions between the rows of blocks; and further that it has been proposed to combine cellular tile blocks with concrete material in such manner that the extent of entry of the concrete 75 material in setting the floor will be limited by the cells or spaces. In the first instance, however, the hollow blocks employed in the crosswise reinforced arch have been such as to preclude the effect of a lock and bond between such tile blocks and the concrete ribs 80 so necessary in a floor possessing the maximum strength with the least dead weight in the materials used, due to the fact, mainly, 85 that the full compressive strength of the material in the hollow blocks cannot be and is not secured when combined with the concrete beams; whereas in the second instance, 90 herein referred to, the hollow tile blocks are set in rows, with the tiles of each row in 95 sidewise contact so that it is not possible for concrete ribs or metal reinforcing rods to extend between the sides of the tile blocks, thus decreasing the efficiency and 100 weight carrying capacity of the floor construction, although it is proposed to cut away the top and side portions of the blocks at the ends thereof in order that the solid material at the bottom of the blocks may 105 project in a manner to produce a lip which produces, first, a solid under surface of clay material at the bottom of the floor whereon to apply the plaster coat; and second, to provide a continuous channel between the 110 ends of two rows of tile blocks, which chan-

nels are designed to receive metal reinforcements and concrete material, the latter closing the hollow spaces in the ends of the blocks and producing beams which extend 5 in one direction only in the floor, *i. e.*, at right angles to the girders. Manifestly, in the latter form of construction the tile blocks are not enveloped on all their sides with the material forming the concrete ribs. 10 and said blocks are not, and cannot be, combined with the concrete material to secure the full compressive strength of the hollow blocks in the construction of the floor or arch.

15 According to my invention, I employ crossing or intersecting metal reinforcing rods which constitute tension members at the bottom middle portion of the floor, hollow tile blocks of cellular form internally 20 and open at the respective ends thereof, said blocks being individually spaced with respect to every other block and occupying a predetermined spaced relation to the crossing metal reinforcements so that the tile 25 blocks are positioned in rows both lengthwise and crosswise of the resulting floor, and bonding material composed of concrete which is poured and tamped so as to fill the spaces intervening the sides and ends of the 30 hollow tile blocks, whereby the concrete material produces intersecting beams which envelop the side walls and end portions of the hollow tile blocks, so as to secure a perfect bond between the dry material of preferably 35 baked hollow tiles and the wet plastic or semi-plastic concrete, such bond existing not only at the side walls of the individual tiles but also at the end faces of said tiles. Furthermore, the cellular hollow tiles and the 40 material of the concrete beams are intimately locked and bound together for the reason that the concrete material, while in its plastic or semi-plastic condition, will enter and fill the hollow spaces of said tiles at 45 the open ends thereof, but the extent of entry of such concrete material will not be unduly excessive for several reasons, first, the material will flow into the open ended spaces to an extent limited and determined 50 by the angle of repose of such material, second, by the cross sectional area of the openings or the cell spaces at the end of the tile block, and third, by the resistance to the inflow due to the friction between the walls of 55 the cell space and the plastic concrete material. The concrete material thus entering the cell spaces at the open ends of the tile block results not only in a perfect bond between such material but it secures the added 60 advantages of, first, a mechanical lock between the concrete beam and the hollow tile block, second, the material thus admitted to the ends of the cell spaces in conjunction with the concrete material in external contact with the respective side walls of the 65

tile block coöperate in laterally strengthening the walls of the block so as to impart added strength and resisting qualities laterally to the blocks, and, third, the tile blocks are so combined with the concrete beams as 70 to attain the full compressive strength of said tile blocks in the floor construction, whereby there results a floor structure characterized by an increase of fully fifteen per cent. in strength with a decrease of not less 75 than ten per cent. in weight of materials as compared with any prior floor structure of which I have knowledge.

In a practical form of construction the floor is in the form of a flat slab the concrete 80 material of which is integral with a belt course, said concrete material extending continuously over the tops of the piers and interior columns whereby I am enabled to secure the important function of continuous 85 floors between the girders and over the tops of the piers and columns. Furthermore, the metal reinforcing rods or bars are embedded in the concrete beams, and said bars or rods are so positioned that at the middle of the 90 floor between the girders and piers (at the bottom chord of the flat arch) the rods act as tension members whereas the tile blocks and concrete ribs are in compression at the top chord of the arch; but in carrying the 95 continuous metal rods or bars over the capitals of the piers or columns, the said rods or bars are at or near the top of the concrete 100 slabs over such piers or columns, so that they resist the tension of the slab at the top chord at the specified particular points.

Other features and advantages of the invention will appear from the following detailed description taken in connection with the drawings.

In the drawings, Figure 1 is a plan view of a portion of a floor embodying my invention, the full lines representing the relative positions of the hollow tile blocks and the concrete beams, whereas the dotted lines 110 illustrate the relation of the crossing or intersecting metallic bars or rods to the tile blocks and the concrete beams. Fig. 2 is a vertical section showing two floors of a building, certain piers and columns and the 115 belt course. Fig. 3 is an enlarged detail section on the line 3—3 of Fig. 1, and Fig. 4 is an enlarged detail section on the line 4—4 of Fig. 1.

Referring now to the drawings, 10 designates the columns and 11 the piers of the building, both of which perform the function of supporting the floors and walls. As is usual the piers are at the side walls of the building, whereas the columns are in the interior. Said piers and columns may be of any suitable or preferred construction, but preferably they are formed of reinforced concrete. The columns and the piers are constructed with enlarged upper ends or 120

capitals, as indicated at 10^a and 11^a in Fig. 2, thus affording wide bearings for the floor slab.

The floor is a flat slab composed of concrete 12, filling blocks 14, and metal reinforce bars or rods 15. Said floor slab extends continuously over the tops or capitals of the piers and the columns, the floor slab being bounded at its edges by a belt course 16 which is shown in the form of a deep concrete beam extending between the caps of the piers, and preferably formed integral with the concrete 12 of the floor. It will be observed that the floor is of uniform thickness and furthermore is free from beams or girders at its lower surface.

The filling blocks 14 are composed preferably of terra cotta tile or other earthenware material, the said filling blocks thus combining strength and light weight with fireproof and sound-deadening qualities. Each terra cotta or tile block is hollow but is provided interiorly thereof with a number of walls 14^a, shown more particularly in Figs. 3 and 4, whereby the block is divided interiorly into a number of cells or passages. The ends of the block are open, whereas the sides, top and bottom are closed by the walls of the block. The cells or passages extend lengthwise through the block so that when the plastic or semi-plastic concrete material is tamped into place to produce a resulting concrete beam or rib, said plastic or semi-plastic concrete will enter the cells or passages at the respective open ends of the block. The entry of the concrete material while in a plastic or semi-plastic condition will be limited by the vertical dimensions of the cells or passages and by the resistance due to the frictional contact of said material with the walls formed by the interior partitions, as a result of which the plastic or semi-plastic material will produce a shoulder the top of which is inclined, as represented more particularly in Fig. 4 so that the plastic or semi-plastic concrete material will result in a surface conforming to the angle of repose of the material. The plastic or semi-plastic concrete produces a beam or rib and substantially fills the open end portions of the hollow tile blocks, thereby resulting in a positive direct interlocking engagement between the ends of the hollow tiles and the material composing the concrete beams.

As shown, the hollow tile blocks are spaced from each other on all sides and ends, and when the concrete material is tamped said material surrounds each side and end of all the blocks, thus resulting in a monolithic structure, all the parts of which are inseparably united and homogeneous.

The hollow tile filling blocks 14 are omitted over the columns and the piers and at the points where the floor meets the be-

course 16, thus resulting in the production of a solid concrete slab which secures increased strength at the points where increased strength is required, owing to the strains incident to the load upon the floor. In order to further strengthen the structure, I omit the rows of hollow tile blocks from the piers of the next adjacent columns, thereby producing solid concrete slabs 12^a extending between the piers, adjacent to the columns, and virtually forming concrete girders in the plane of the floor.

The reinforce consists of iron rods or bars 15 extending through or embedded in the concrete ribs and positioned between the rows of hollow tile blocks. Certain of the rods or bars extend in one direction and parallel to the belt course, whereas other rods extend at right angles to the belt courses so as to cross the first-named rods, whereby the floor slab is strengthened materially by the crossing rods or bars embedded in the concrete beams. It is to be understood that the rods extending in one direction are positioned between the rows of tiles at the closed sides thereof, whereas the rods which extend in the opposite direction are positioned between the rows of tiles adjacent to the open ends thereof, and thus the rows of tiles extend in two directions and the rows of rods or bars also extend in two directions so that the continuous rods or bars will cross or intersect at points adjacent to the corners of the individual tiles, as a result of which construction a network of reinforcing bars or rods and a similar net-work of intersecting concrete beams is produced in the floor slab for the purpose of imparting thereto great strength and weight-carrying capacity.

The rods or bars are anchored at the upper portion of the floor slab and extend downward therein to the lower portion or chord of the slab, substantially as shown in Fig. 2, certain of said rods or bars extending across to the solid concrete slabs 12^a between the columns. At these slabs the rods or bars rise to the upper portion of the floor slab, near the top surface thereof, and they pass beyond the slabs 12^a down into the floor at the opposite side of said slabs 12^a. By extending the reinforcing rods or bars along the bottom chord of the floor slab between the columns and piers the tension stresses in the floor slab at this point are resisted while by extending the rods or bars across the upper portion of the floor slab between the columns the tension strains at these points are again resisted. This is due to the fact that between the columns, the top chord of the floor slab is in compression and the bottom chord of the floor slab is in tension, while at the columns and at the belt course the top chord of the floor slab is in tension and the bottom chord is in compression. As

shown the belt course 16 is independently reinforced by suitable bars or rods 15^a extending longitudinally of said belt course.

At the top portions of the floor slab exposed to the greatest stress the bars or rods are positioned in overlapping relation, thus imparting increased strength at such points of overlap. Thus, at the slabs 12^a, and at the solid concrete slabs between the columns, 10 the ends of the bars or rods are extended past each other, thereby doubling the effect of the reinforce at such points. Furthermore, the overlapping of the rods or bars is effected at all the lines running between the 15 columns within the interior of the building, producing reinforce areas in the nature of internal girders reaching from column to column, thereby bracing and strengthening the building into a rigid unitary structure. 20 Obviously, the walls of the building do not form any part of the present invention and are not illustrated. As hereinbefore stated, the building is particularly adapted for manufacturing and business purposes, and 25 as is usual in such cases the walls are usually skeletonized allowing the largest possible window area to insure a well lighted interior.

In installing the arch the reinforce and 30 the hollow tile blocks are positioned substantially as shown in Fig. 1, the reinforce being put into place during or immediately before the tamping of the concrete. It is preferred to position the metallic rods or 35 bars in crossing relation and immediately thereafter to place the hollow tile blocks in the spaces between said crossing bars and at regular uniform distances therefrom. As is usual in the art, the hollow tile blocks are 40 supported by a centering and the rods and bars having been properly positioned, the concrete in a plastic or semi-plastic condition is poured into the spaces between the rows of tiles, such concrete being tamped in 45 place. The plastic or semi-plastic concrete is in direct contact with the side walls and ends of the tile blocks so as to secure a perfect bonding effect therewith, and by tamping the concrete material in place the mass 50 is solidified to a certain extent and some of the concrete flows into the cells or spaces at the respective open ends of the hollow tiles, the extent of entry of the plastic or semi-plastic material being limited, first, by the 55 angle of repose of such material, second, by the relatively small cross sectional area of the cell spaces within the hollow tiles, and third by the resistance due to the frictional contact between the walls of the cell spaces 60 and the inflowing material. When the concrete sets and hardens a net-work of intersecting ribs results, which ribs are so intimately united to the sides and ends of the hollow tile blocks as to result in a homo-

geneous structure. Furthermore, the hollow 65 tile blocks are so united to the concrete beams as to utilize the full compressive strength of the material in the tile blocks, and while the tile blocks tend to decrease the dead weight of the floor slab, yet said tile 70 blocks and the metal reinforcing rods are so combined with the concrete beams as to result in a monolithic structure possessing great weight-carrying or load resisting capacity. Furthermore, the walls and partitions of the tile blocks are in contact with the concrete ribs and the inwardly extending projections of such ribs so that the walls and the partitions of the tile blocks are laterally reinforced, thus materially strengthening 75 the blocks themselves and adding weight-resisting capacity thereto.

In addition to the foregoing functions, the floor slab of my invention possesses other numerous advantages. The structure is extremely light in weight and easy of installation, for the reason that the centering or molds in which the work is shaped may be perfectly flat owing to the fact that the bottom of the floor slab is flat. This effects a 85 great saving, for the reason that the hollow tile blocks may be placed in position on the centering and the rods or bars placed in the desired relation to the tile blocks by unskilled labor, the operation of assembling 90 the blocks and the rods being rapidly performed, after which it is only necessary to dump the concrete material into place and to tamp such concrete material.

In some prior floor slabs the hollow blocks 100 have been arranged so that there was a lack of firm connection between said hollow blocks and the concrete material, resulting in a failure to transmit stresses uniformly from the concrete to the blocks; but in my invention the concrete material enters to a 105 substantial extent into the cells or spaces at the open ends of the blocks, thereby securing a substantial interlocking engagement and a firm connection between the concrete material of the beams and the end portions of the blocks. Not only is the concrete material interlocked with the open end portions of the blocks, but said material is perfectly bonded with the filling blocks at the side 110 walls and at the ends of said blocks, whereby the blocks operate effectually as compression members, and the concrete material in such intimate contact with the side walls 115 imparts strength and stability thereto for 120 resisting the lateral strains.

As will be noted by reference to Fig. 3, the partition walls within the hollow tile blocks are close enough to each other to substantially limit the extent to which the plastic concrete material will enter the cells or spaces within said block, and by varying the area of such cells or spaces the extent of

entry of the concrete material into the same may be controlled. It is my purpose to so proportion the cells or spaces within the blocks that the concrete material will enter to an extent determined by the angle of repose of the material and to secure the desired firm interlocking engagement of said concrete material with the filling blocks, said concrete material operating to brace the partitions against each other and to afford the equivalent of a solid end wall, thus materially strengthening the blocks themselves.

Having thus fully described the invention, what I claim as new and desire to secure by Letters Patent is:

1. A crosswise reinforced floor slab comprising rows of hollow tile blocks, each block being provided with vertical sides and having openings which extend through opposite ends of said block, two series of intersecting concrete beams in contact with the vertical sides and the open ends of said tile blocks, each block being interlocked at the open ends thereof with the concrete beams, the height of said beams being equal to the thickness of the floor slab, and two series of rods the rods of each series extending continuously with respect to said rows of blocks, said blocks being separated and the rods being spaced relatively to the blocks to provide spaces to admit of tamping the material which enters into the formation of the beams.

2. A crosswise reinforced floor slab comprising hollow blocks extending in rows in two directions, each block having closed sides and provided with openings which extend through the block and open through opposite ends thereof, two series of concrete beams extending in two directions and bonded to the blocks, some of the concrete material of the beams filling the end portions of said openings within said blocks, and two series of rods, the rods of each series extending continuously with respect to rows of said blocks, said blocks and the rods being positioned relatively to each other to provide spaces admitting the passage of the material which enters into the formation of the beams.

3. A crosswise reinforced floor slab comprising hollow blocks assembled in rows extending in two directions, each block having closed sides and provided with openings which extend through the block and open through opposite ends thereof, two series of concrete beams bonded to the blocks, said open ends of the passages in said blocks being proportioned to admit limited quantities of the concrete material to the interior of the block, said admitted concrete material imparting stiffness to the block sidewise thereof so as to render the sidewise compressive strength of the block equal to the

endwise compressive strength thereof, and two series of rods, the rods of each series extending continuously with respect to rows of blocks, said blocks and the rods being positioned relatively to each other to provide spaces admitting the passage of the material which enters into the formation of the beams.

4. A crosswise reinforced floor slab comprising hollow blocks assembled in rows and each spaced with respect to adjoining blocks, each block having closed sides and provided with a series of openings which extend through said block and open through opposite end portions thereof, two series of concrete beams extending in two directions and bonded directly to the blocks, some of the concrete material filling the end portions of said openings in said blocks, the cross sectional area of the beams extending in one direction being equal substantially to the cross sectional area of the beams extending in the other direction, and two series of rods, the rods of each series extending continuously with respect to rows of blocks, said blocks being separated and the rods being positioned relatively to the blocks to provide free spaces of ample size to admit of tamping the material which enters into the formation of the beams.

5. A crosswise reinforced floor slab supported on columns and comprising hollow blocks assembled in rows extending in two directions, each block having closed sides and provided with a series of passages extending through the block and opening through the opposite ends thereof, two series of rods, the rods of each series extending continuously with respect to rows of blocks, said blocks being relatively separated and the rods being so positioned with reference to the blocks as to provide spaces for the tamping of concrete adapted to enter into the formation of beams, and two series of concrete beams bonded to said blocks, said open ends of the blocks admitting into the passages thereof the inflow of plastic concrete material to an extent limited by the angle of repose of said plastic material.

6. A crosswise reinforced floor slab supported on columns and comprising hollow blocks assembled in rows extending in two directions, each block having closed sides and provided with interior webs positioned to form a series of passages which extend through the block and open through the end portions thereof, two series of rods the rods of each series extending continuously with respect to rows of blocks, said blocks being relatively separated and the rods being positioned with respect to the blocks so as to form spaces for tamping of concrete material adapted to enter into the formation

of beams, and two series of concrete beams bonded to the blocks, said open ends of the blocks admitting the inflow into said passages of plastic concrete material to an extent limited by the frictional contact of said plastic material with the webs forming said longitudinal passages.

In testimony whereof I have signed my name to this specification in the presence of two subscribing witnesses.

KARL R. SCHUSTER.
